(57) **CLAIM**

The ornamental design for a packaging container, as shown and described.

DESCRIPTION

FIG. 1 is a perspective view of a packaging container, showing my new design.

FIG. 2 is a perspective view thereof showing the lid off to show aspects of the design not clearly visible when combined.

FIG. 3 is a front view thereof.

FIG. 4 is a rear view thereof.

FIG. 5 is a top plan view thereof.

FIG. 6 is a bottom plan view thereof.

FIG. 7 is a right side view thereof.

FIG. 8 is a left side view thereof; and,

FIG. 9 is a sectional view taken along line 9-9 of FIG. 3 thereof.

In the drawings, the evenly spaced broken lines in the figures illustrate the portions of the design that form no part of the claimed design. The dot-dash lines illustrate a boundary to the claim and form no part thereof.
